Atty.

UNITED STATES PATENT OFFICE.

LEO J. WAHL, OF STERLING, ILLINOIS.

CLIPPER.

Application filed July 6, 1920. Serial No. 394,055.

To all whom it may concern:

Be it known that I, LEO J. WAHL, a citizen of the United States, and a resident of Sterling, in the county of Whiteside and

5 State of Illinois, have invented certain new and useful Improvements in Clippers, of which the following is a full, clear, and exact description, reference being had to the accompanying drawing, forming part of 10 this specification.

My invention relates primarily to clippers intended for use in barber shops, though it is capable of use for clipping the hair of animals and for clipping other material 15 than hair.

20 A clipper constructed in accordance with my present invention is intended to be operated by an alternating electric current its principle of operation being the provision of an electromagnet or magnets co-operating with an armature bar in such manner that the alternations of the current will vibrate the armature bar to operate the movable clipper blade.

25 One object of my invention is to so construct and mount the armature bar that its tension against vibration may be varied.

Another object of my invention is to so 30 connect the movable clipper blade to the armature bar that it will be held in proper position with relation to the stationary clipper blade through the means of a spring tension device, the spring tension device serving also as a driving connection.

Another object of my invention is the provision of means for adjusting the position of the armature bar to vary the amount of pressure of the spring tension device between the armature bar and the movable 40 clipper blade.

Other objects of my invention will appear and be described in the specification.

The novelty of my invention will be hereinafter more fully set forth and specifically 45 pointed out in the claims.

In the accompanying drawing:—

Fig. 1 is a plan view of a clipper embodying my invention, the cover of the case being removed.

50 Fig. 2 is a sectional side elevation of the device, the rear wall of the case being removed.

Fig. 3 is a front end elevation of Fig. 1, the stationary and movable clipper blades being removed.

Fig. 4 is a sectional end view taken on the dotted line 4—4 of Fig. 1 looking to the right.

The same numerals of reference are used to indicate identical parts in all the figures.

In its preferred form of construction the clipper comprises a case 1 within which a pair of electromagnets or solenoids 2 are mounted. An armature bar 3 is attached to a blade spring 4, the latter being mounted 65 in the case by means of a bolt 5, the bolt 5 exerting its strength to force the blade spring 4 against the end of the adjusting screw 6, it being noted that the end of the blade spring 4 rests against a shoulder 7 70 of the case 1 so that after the bolt 5 is tightened the blade spring 4 is forced into contact with the adjusting screw 6. The armature bar 3 is bent approximately at right angles as at 8 and is then slightly twisted 75 as shown more clearly in Fig. 2, and a spring driving member 9 is attached thereto as by screws 10. The spring driving member 9 is curved as shown more clearly in Fig. 2 and a carrier 11 is attached thereto, the carrier 80 11 being provided with driving lugs 12 shown more clearly in Figs. 2 and 3 which engage suitable openings in the movable clipper blade 13 the latter co-operating with the stationary clipper blade 14 which is secured to the case 1 by screws 15 in the threaded holes 16 of the case 1. The blades 13 and 14 are preferably of the same or a similar construction as those used in the ordinary hand operated hair clipper so that 85 they may be interchangeable with the hand operated device. An additional pair of curved blade springs 17 are held in place on the armature bar by the screws 10 and assist the spring driving member 9 in holding the 90 clipper blades in proper operating contact.

The blade spring 4 is perforated as at 18 at a point adjacent the bolt 5 and the reduced end of a bar 19 enters the perforation, the other end of this bar resting on a 100 pedestal 20 which is a part of the case 1, a screw 21 being provided and passing through the bottom of the case 1 and being threaded through the bar 19, the screw 21 being located adjacent the blade spring 4, 105 the construction being such that when the screw 21 is turned in the direction of the lead of its thread, the bar 19 will be pulled toward the bottom of the case 1 and will swing the blade spring 4 on the bolt 5, 110

thereby moving the free end of the armature bar downward to close the springs 9 and 17 to press the movable clipper blade 13 against the stationary clipper blade 14.

The cover 22 of the case 1 is bent downwardly as at 23 and a guard 24, preferably made of thin sheet metal and perforated to be embraced by the driving lugs 12, is fitted between the carrier 11 and the movable clipper 10 blade 13, the guard 24 being shaped to overlap the edge of the portion 23 of the cover 22 to prevent any hair or other foreign substance from entering the interior of the case, this part of the construction being best 15 shown in Fig. 2, the guard 24 being omitted from Fig. 1.

The rear of the case 1 is perforated and a coil spring 25 is passed through this perforation to serve as a guard for the cable 20 26 which supplies the current for the electro-magnets 2, the circuit being a simple series connection from one terminal of the cable 26 through one of the electro-magnets 2 thence to the other electromagnet and 25 through the same to the other terminal of the cable 26.

After having set the tension of the movable clipper blade with relation to the stationary blade through the means of the adjusting screw 21, the cable 26 is connected to 30 alternating current and the vibratory action of the armature bar is adjusted through the adjusting screw 6, whereupon the device is ready for use.

35 To remove the clipper blades from the device it is only necessary to remove the screws 15 whereupon the stationary clipper blade may be lifted out of position thus exposing the underface of the movable clipper 40 blade which may then be lifted from its engagement with the driving lugs 12 and the blades either resharpened or replaced as occasion may require.

45 While I have shown the adjustment for the spring driving member 9 as consisting of the bar 19 and screw 21, it is apparent that provision may be made for adjusting the position of the stationary clipper blade 14 toward and from the movable clipper 50 blade 13, or the movable clipper blade 13 might be rigidly mounted with relation to the portion 8 of the armature bar 3 and the stationary clipper blade be provided with a spring tension device which might be either 55 adjustable or non-adjustable but which would hold the clipper blades yieldingly in operative relation.

60 It is to be noted that the spring 4 is made sufficiently heavy so that it will have strength enough to prevent the armature 3 from striking the ends of the pole pieces during the operation of the device, this spring acting as a movement limit for the travel of the armature in the direction to- 65 wards the pole pieces.

Having thus fully described my invention I claim:

1. In a clipper the combination of a case, a clipper blade carried thereby, a movable clipper blade co-operating with the first 70 mentioned blade, an electro-magnetic clipper blade driving mechanism, and a yielding driving connection between the clipper blade driving mechanism and the movable clipper blade for driving the blade and holding it 75 to its seat.

2. In a clipper the combination of a stationary clipper blade, a movable clipper blade co-operating therewith, an electro-magnetic blade moving mechanism carried by 80 the carrier for the stationary clipper blade and a yielding driving connection between the blade moving mechanism and the movable clipper blade.

3. In a clipper comprising a case carrying 85 a stationary clipper blade and a movable clipper blade, the combination of a moving element, electro-magnetic means for moving the latter, a yielding driving connection between the moving element and the movable 90 clipper blade, and means for moving the moving element in a direction other than that required to impart movement to the clipper blade to subject the yielding driving connection to pressure to hold the movable clipper 95 blade in proper operative position to the stationary clipper blade.

4. In a clipper the combination of a case, a clipper blade carried thereby, a movable blade co-operating with the first mentioned 100 blade, an electromagnet carried by the case, a circuit for the magnet, a spring carried armature bar, a driving connection between the armature bar and the movable clipper blade, and means for adjusting the tension 105 of the spring which carries the armature bar.

5. In a clipper the combination of a case, a clipper blade carried thereby, a movable clipper blade co-operating with the first 110 mentioned blade, an electromagnet carried by the case, a circuit for the magnet, a spring carried armature bar co-operating with the electromagnet, a yielding driving connection between the armature bar and the movable 115 clipper blade, means for subjecting the yielding driving connection to tension, and means for adjusting the tension of the spring carried armature bar.

6. A device of the character described 120 comprising a supporting member, a cutting blade movably mounted thereon, electromagnetic means for moving said blade in one direction, and spring means for moving said blade in the opposite direction, said spring means having a weakened portion.

7. A device of the character described 125 comprising a supporting member, a cutting blade movably mounted thereon, and means for vibrating said cutting blade comprising 130

- a driving link and electromagnetic means for moving said link and blade in one direction energized from a source of alternating current and spring means extending parallel to said link for moving said blade in the opposite direction, said spring means having a weakened portion to tune the moving parts of said device to the frequency of said source of current.
10. A device of the character described comprising a supporting member, a cutting blade movably mounted thereon, and driving means for said blade comprising electromagnetic means for moving said blade in one direction, and spring means for moving said blade in the opposite direction, said spring means having a weakened portion between the ends thereof.
15. A device of the character described comprising a support, a reciprocable blade mounted on said support, and means for reciprocating said blade comprising an electromagnet, and an armature adapted to be vibrated thereby, said magnet and said armature being relatively adjustable.
20. A device of the character described comprising a casing having a cover member, a blade fixed relative to said casing, a blade mounted to reciprocate transversely of said first mentioned blade, means for reciprocating said blade, adjustable tension means within the casing for pressing said blades into engagement and adjusting means extending outside said casing, said tension means being held within said casing independently of said cover.
25. A device of the character described comprising a support, a blade fixed relative to said support, a blade mounted to move transversely of said first mentioned blade, tension means within said casing for holding said movable blade in engagement with said fixed blade, a vibrating armature, an electromagnet for actuating said armature and a driving connection between said armature and said movable blade, said driving connection being independent of said tension means.
30. A device of the character described comprising a casing, a movable blade mounted on said casing, and means for moving said blade comprising an electromagnet and an armature cooperating therewith, said casing being provided with means to hold said electromagnet from rattling therein.
35. A device of the character described comprising a casing, a toothed blade fixed relative thereto, a movable blade cooperating therewith, and means for moving said blade, said movable blade having means within said casing independent of said other blade for guiding the movements thereof so that the forward edge thereof will move substantially parallel to the forward edge of the fixed blade.
40. A device of the character described comprising a stationary toothed blade, a toothed blade mounted to reciprocate relative to said stationary blade, and means for reciprocating said blade comprising an electromagnet and an armature adapted to be vibrated thereby, said electromagnet and armature being relatively adjustable without changing the relative position of the teeth on said blades.
45. A device of the character described comprising a support, a reciprocable blade mounted on said support, means for reciprocating said blade comprising an electromagnet, and an armature adapted to be vibrated thereby, and means for adjusting said armature relative to said magnet.
50. A device of the character described comprising a casing, a blade mounted to reciprocate relative to said casing, means within said casing for reciprocating said blade comprising an electromagnet, and an armature adapted to be vibrated thereby, and means extending outside of the said casing for adjusting said armature relative to said magnet.
55. In a clipper the combination of an electro-magnetic coil, an armature for the coil, and a spring for mounting the armature to permit it to move to a point short of contact with the pole piece of the coil thereby providing a movement limit.
60. In a clipper the combination of an electro-magnetic coil, an armature for the coil, a spring for carrying the armature and permitting it to move to a point short of contact with the pole piece of the coil, and means for adjusting the spring.
65. In a clipper the combination of an alternating current electro-magnetic coil, an armature for the coil, and a spring for carrying the armature and permitting it to move to a point short of contact with the pole piece of the coil and for moving it to a point away from the pole piece of the coil during the intervals between the periods of attraction.
70. In a clipper the combination of an alternating current electro-magnetic coil, an armature for the coil, and a spring for carrying the armature and permitting it to move to a point short of contact with the pole piece of the coil and for moving it to a point away from the pole piece of the coil during the intervals between the periods of attraction and means for adjusting the spring.
75. In a clipper a combination of a handle carrying a stationary serrated clipper blade, a movable serrated clipper blade cooperating therewith, an electro-magnetic coil mounted in the handle, an armature for the coil and for moving the movable clipper blade, and a spring for mounting the armature and affording movement limits for its travel ap-

proximately equal to the spacing of the serrations of the blades.

22. In a clipper the combination of a case, a stationary blade carried thereby, a movable blade cooperating with the stationary blade, an armature for operating the movable blade, an electro-magnetic device for moving the armature, a mounting for the armature, and means for applying pressure to the armature to hold the blades in operative relation, said means acting adjacent the mounting for the armature.

23. In a clipper the combination of a case, a stationary blade carried thereby, a movable blade cooperating with the stationary blade, an electro-magnet in the case, blade moving means comprising in part an armature and for moving the movable blade, and means for applying pressure to the blade moving means said pressure means acting at a point approximating the point of minimum movement of the blade operating means.

24. In a clipper the combination of a case, a stationary blade carried thereby, a movable blade cooperating with the stationary blade, an electro-magnet in the case, an ar-

mature for the magnet and for moving the movable clipper blade, a yielding connection between the armature and the movable clipper blade, said connection being yielding in a direction other than the direction of movement of the blade, and means for applying pressure to the movable blade to hold it in operative relation to the stationary blade, said means operating at a point having less movement than the movement of the movable blade.

25. In a clipper the combination of a case, a stationary blade carried thereby, a movable blade cooperating with the stationary blade, an electro-magnet in the case, an armature cooperating with the electro-magnet and for moving the movable blade, means for applying yielding pressure to the movable blade to hold it in operative relation to the stationary blade, a portion of said means moving with the movable blade, an abutment for the pressure means, the movable blade having greater movement than the movement between the pressure means and its abutment.

LEO. J. WAHL.

DISCLAIMER.

1,487,189.—*Leo J. Wahl*, Sterling, Ill. CLIPPER. Patent dated March 18, 1924.
Disclaimer filed August 29, 1927, by the patentee.

Hereby enters this disclaimer to claims 4, 9, 10, 11, 15, 16, 17, 18, 19, 20, 21, and 22 of the specification as issued in said Letters Patent No. 1,487,189, and which are in the following words, to wit:

“4. In a clipper, the combination of a case, a clipper blade carried thereby, a movable blade co-operating with the first mentioned blade, an electromagnet carried by the case, a circuit for the magnet, a spring carried armature bar, a driving connection between the armature bar and the movable clipper blade, and means for adjusting the tension of the spring which carried the armature bar.”

“9. A device of the character described comprising a support, a reciprocable blade mounted on said support, and means for reciprocating said blade comprising an electromagnet, and an armature adapted to be vibrated thereby, said magnet and said armature being relatively adjustable.

“10. A device of the character described comprising a casing having a cover member, a blade fixed relative to said casing, a blade mounted to reciprocate transversely of said mentioned blade, means for reciprocating said blade, adjustable tension means within the casing for pressing said blades into engagement and adjusting means extending outside said casing, said tension means being held within said casing independently of said cover.

“11. A device of the character described comprising a support, a blade fixed relative to said support, a blade mounted to move transversely of said first mentioned blade, tension means within said casing for holding said movable blade in engagement with said fixed blade, a vibrating armature, an electromagnet for actuating said armature and a driving connection between said armature and said movable blade, said driving connection being independent of said tension means.”

“15. A device of the character described comprising a support, a reciprocable blade mounted on said support, means for reciprocating said blade comprising an electromagnet, and an armature adapted to be vibrated thereby, and means for adjusting said armature relative to said magnet.

“16. A device of the character described comprising a casing, a blade mounted to reciprocate relative to said casing, means within said casing for reciprocating said blade comprising an electromagnet, and an armature adapted to be vibrated thereby, and means extending outside of the said casing for adjusting said armature relative to said magnet.

“17. In a clipper the combination of an electro-magnetic coil, an armature for the coil, and a spring for mounting the armature to permit it to move to a point short of contact with the pole piece of the coil thereby providing a movement limit.

“18. In a clipper the combination of an electro-magnetic coil, an armature for the coil, a spring for carrying the armature and permitting it to move to a point short of contact with the pole piece of the coil and means for adjusting the spring.

“19. In a clipper the combination of an alternating current electro-magnetic coil, an armature for the coil, and a spring for carrying the armature and permitting it to move to a point short of contact with the pole piece of the coil and for moving it to a point away from the pole piece of the coil during the intervals between the periods of attraction.

“20. In a clipper the combination of an alternating current electro-magnetic coil, an armature for the coil, and a spring for carrying the armature and permitting it to move to a point short of contact with the pole piece of the coil and for moving it to a point away from the pole piece of the coil during the intervals between the periods of attraction, and means for adjusting the spring.

“21. In a clipper a combination of a handle carrying a stationary serrated clipper blade, a movable serrated clipper blade cooperating therewith, an electro-magnetic coil mounted in the handle, an armature for the coil and for moving the movable clipper blade, and a spring for mounting the armature and affording movement limits for its travel approximately equal to the spacing of the serrations of the blades.

“22. In a clipper the combination of a case, a stationary blade carried thereby, a movable blade cooperating with the stationary blade, an armature for operating the movable blade, an electro-magnetic device for moving the armature, a mounting for the armature, and means for applying pressure to the armature to hold the blades in operative relation, said means acting adjacent the mounting for the armature.”
